UNITED STATES PATENT OFFICE.

AUSTIN A. CROSSLEY, OF LUTHER, OKLAHOMA.

LOCKING-VALVE FOR INTERNAL-COMBUSTION ENGINES.

1,382,480.

Specification of Letters Patent. Patented June 21, 1921.

Application filed February 18, 1920. Serial No. 359,713.

To all whom it may concern:

Be it known that I, AUSTIN A. CROSSLEY, citizen of the United States, residing at Luther, in county of Oklahoma and State 5 of Oklahoma, have invented certain new and useful Improvements in Locking-Valves for Internal-Combustion Engines, of which the following is a specification.

This invention relates to an improved 10 locking valve for motor vehicles and has as one of its principal objects to provide a device of this character whereby the flow of fuel gases from an engine carburetor to the engine of a motor vehicle may be prevented 15 for thus in turn preventing unauthorized operation of the vehicle.

The invention has as a further object to provide a device wherein, when the valve of the device is locked in closed position, the 20 valve will itself serve to lock the fastenings securing the device in place so that removal of the device when locked will be prevented.

And the invention has as a still further 25 object to provide a device which may be employed in connection with substantially any conventional type of internal combustion engine.

Other and incidental objects will appear hereinafter.

30 In the drawings:

Figure 1 is a side elevation showing my improved device interposed between a conventional type of carburetor and engine intake manifold,

35 Fig. 2 is a fragmentary sectional view taken medially through the device, the valve of the device being open,

Fig. 3 is a vertical section on the line 3-3 of Fig. 2, and looking in the direction 40 of the arrows,

Fig. 4 is a fragmentary perspective view showing the mechanism employed for actuating the valve, and

Fig. 5 is a detail perspective view of one 45 of the fastening devices employed for securing the device in active position as shown in Fig. 1.

Referring more particularly to the drawings, I have shown my improved locking 50 valve in connection with a conventional type of engine intake manifold 10 and carburetor 11. In carrying the invention into effect, I employ a valve casing which is formed of mating sections 12 and 13 respectively, the 55 section 12 being in the nature of a body section and the section 13 a cover plate there-

for. The section 13 is detachably secured to the section 12 by screws or other approved fastening devices and formed in the section 12 is, as particularly shown in Fig. 3, a vertical recess 14. Intersecting this recess is a gas passage 15 through the casing and within the recess is a valve 16. The recess is provided with a reduced lower end portion in which is countersunk a plate 17, this plate being provided at three of the sides thereof with side flanges coacting with the walls of the recess. Struck from the plate are stop lugs 20 and 21 respectively and mounted upon the section 12 to project at its inner end through the plate is a lock casing 22 which rotatably receives the lock barrel 23 operable by a key 24. The inner end of the barrel is, as shown in detail in Fig. 4, provided with a reduced extension 25 which rotatably receives a collar 26 having a radial arm 27 and an oppositely directed stop lug 28. Screwed or otherwise secured against the end face of the extension 25 is an end plate 29 provided with a radial lug 30, it being observed that the arm 27 is offset laterally from the collar 26 so that the lug 30 may coact with said arm. Extending between the free end of the arm and the valve 16 is a connecting rod or link 31 pivotally connected to the arm and valve.

As will now be observed, the upper end portion of the casing of the valve is formed to fit between the confronting flanges of the manifold 10 and carburetor 11 mating therewith and engaged through these flanges and through the casing are bolts 32 securing the device in position with the gas passage 15 registering with the passages of the carburetor and manifold, the bolts being inserted first through the flange of the manifold and threaded into the flange of the carburetor. As particularly brought out in Fig. 3, the recess 14 of the section 12 of the valve casing intersects the bolt openings through the casing and the bolts are provided with reduced squared portions 33 which, when the bolts are in place, lie at opposite sides of the recess, the bolts being so positioned that one of the flat faces of each of these squared portions alines with one of the end walls of the recess so that the valve 16 may shift freely between the squared portions of the bolts. Consequently, by turning the key 24 in one direction, the lug 30 upon the plate 29 of the lock barrel will be moved to coact with the arm 17 for

2

rotating the collar 26 and consequently swinging the arm 27 for shifting the valve 16 downwardly to closed position blocking the passage 15 through the valve casing, this 5 movement of the lock barrel being limited by engagement of the lug 28 of the collar with the stop lug 21 of the plate 17. The key 24 may then be removed when the valve will be locked closed for preventing flow 10 of fuel mixture from the carbureter through the intake manifold to the vehicle engine. Operation of the engine will thus, of course, be prevented to in turn prevent unauthorized use of the vehicle. When the valve 16 15 is thus closed, it will be seen that the ends of the valve will closely confront the inner vertically disposed flat faces of the squared portions 33 of the bolts 32 so that the valve will then coact with these squared portions 20 of the bolts to prevent counter-rotation and removal of the bolts. The valve will therefore serve to lock the bolts against displacement and accordingly lock the device in place between the carbureter and manifold 25 so that the device cannot be removed for effecting operation of the engine. By rotating the lock barrel in a direction opposite to that first described, the arm 27 will be swung for opening the valve when the 30 lug 28 of the collar 26 will abut the stop lug 20 of the plate 17. The key 24 may then be removed when the valve will be locked open. It will accordingly be seen that I provide a particularly effective device 35 for the purpose set forth and a device which may be readily employed in connection with substantially any conventional type of vehicle engine intake manifold and carbureter. Hinged to the casing section 12 40 is a cap 34 which, when the key is removed, may be swung to closed position housing the outer end of the lock casing and a suitable packing is preferably arranged within the cap for closing the keyhole of the lock. 45 Thus, when the valve is locked open and the key is displaced, entrance of air through the lock to cause dilution of the fuel mixture will be prevented.

Having thus described the invention, what 50 is claimed as new is:

1. A device of the character described including a valve casing having a gas passage therethrough, a valve slidable within the casing, a lock carried by the casing and provided with a rotatable lock barrel, a collar 55

freely mounted on the barrel and provided with an arm, an operative connection between the arm and valve, and a plate fixed to the barrel and provided with a lug engageable with the arm whereby the lock 60 barrel may be operated for shifting the valve to closed position blocking said passage.

2. A device of the character described including a valve casing, rotatable means for 65 securing the valve casing in active position, and a valve within the casing movable to closed position locking said means against rotation.

3. A device of the character described including a valve casing, a bolt extending through the valve casing for securing the casing in active position, and a valve within the casing movable to closed position locking the bolt against rotation. 70

4. A device of the character described including a valve casing, a bolt extending through the casing for securing the casing in active position and provided with a flat face, and a valve within the casing movable to closed position confronting the flat face of the bolt for locking the bolt against rotation. 75

5. A device of the character described including a valve casing, bolts extending 80 through the valve casing and provided with reduced squared portions, and a valve within the casing movable to closed position extending between the squared portions of said bolts to coact with the adjacent flat faces 85 thereof for locking the bolts against rotation. 90

6. The combination with an intake manifold and carbureter of a valve casing interposed therebetween, means securing the valve casing in position, and a valve slidably movable to closed position within the casing coacting with said means for locking the casing against displacement. 95

7. A device of the character described including a valve casing, means for securing 100 the valve casing in active position, and a valve within the casing movable to closed position confronting said means whereby said means when moved will impinge the valve for locking the valve against movement and also locking said means against displacement. 105

In testimony whereof I affix my signature.

AUSTIN A. CROSSLEY. [L.S.]
